UNITED STATES PATENT OFFICE.

ADOLF B. HROMAS, OF ULYSSES, NEBRASKA.

HEATER.

Application filed September 29, 1925. Serial No. 59,314.

- It is the purpose of the present invention to provide, in a heater for use in a water tank, a smoke box for the products of combustion with an outlet chimney, a fire-box with pipes of communication with the smoke box, there being a downwardly inclined chute or passage for the fuel so located with respect to the fire-box as to direct the fuel onto the grate the entire heater adapted to be disposed within the tank (which receives water) for heating the contents thereof, the inclined chute or passage terminating at a point above the surface of the water.
- Another purpose is to provide a practical and relatively simple construction of heater which may be located in a tank of water, with a cover on the upper end of the chute or passage which leads to the fire-box, in conjunction with means for setting the cover in different positions to permit a draft to pass through the heater.
- Still another purpose is to provide, in a heater, a fire-box with a grate and a deflector adjacent one end of the grate which can be positioned to direct the fuel onto the grate or the draft under the grate. In other words, the deflector performs a double function.
- It is to be understood that the particulars herein given are in no way limitative and that, while still keeping within the scope of the invention, any desired modifications of detail and desired proportions may be made in the apparatus according to the circumstances.
- The invention comprises further features and combinations of parts to be hereinafter set forth, shown in the drawings and claimed.
- In the drawings:
- Figure 1 is a longitudinal sectional view through a conventional construction of tank, showing it containing water to be heated, with the improved heater in section and mounted therein.
- Figure 2 is a sectional view on line 2—2 of Figure 1.
- Figure 3 is a sectional view on line 3—3 of Figure 1.
- Figure 4 is a detail view showing a reinforcing plate to be used on the interior of the fire-box to brace a removable wall of the latter where pipes from the smoke box connect therewith.
- Referring to the drawings, 1 designates a conventional tank, which may be any size and shape, and 2 denotes a heater which comprises a fire-box 3, which may be any shape and size, including a chimney or smoke flue 4 rising therefrom. The heater also includes a fire-box 5 in the form of a casing 6 which may be any shape and size desired and the smoke box may be constructed of any suitable material, preferably sheet metal.
- One end of the fire-box has an upwardly inclined chute 7 which is tapered toward its upper end, the interior of the chute constituting a passage 8 leading to and communicating with the interior of the fire-box. A suitable grate 9 on supports 10 is mounted within the fire-box. At one end of the grate and swingingly mounted upon the same by means of a shaft 11 is a deflector 12. The grate being loosely mounted in the fire-box and carrying the deflector, the latter may swing to either of the two positions indicated in Figure 1 of the drawings. When in the full line position, air is directed below the grate and through the fuel thereon to provide for the ready combustion of the latter. In the dot and dash line position, the deflector serves to direct onto the grate all fresh fuel with which the fire-box is charged.
- The upper end of the chute is open but is provided with a closure or cover constituting a damper 15 which is carried by the pivot rod 16 spanning the opposite walls at the upper end of the chute. The damper is marginally flanged, as at 17, so as to fit the upper end of the chute, and pivoted at 18 is a toothed support 19. A rod 20 is mounted in the opposed walls of the upper end of the chute and is positioned so as to be engaged by the teeth of the support 19. When the damper or cover is tilted upward, the toothed edge of the support rides over the rod and when the damper is raised to the desired position, the engagement of one of the teeth with the rod holds the damper in a raised position. As shown, the damper or cover is partly raised, which allows a slight draft to pass down through the chute and under the grate to percolate through the bed of the fire.
- The products of combustion pass through the tubes or pipes 21. In the illustrated embodiment, nine tubes or pipes are shown of which five are in the top row and four in the bottom row. There may be as many used, however, as desired and they may be short or long or any length found to meet the re-

quirements under which the invention is used. Where they connect with the smoke box, a casting 22 is employed through which the pipes are threaded. The casting 22 is in the form of a plate, and washers are disposed on the front and rear faces of this plate and engaged by nuts 24 which serve to hold the washers in position and insure a rigid connection of the pipes with the casting.

A cover plate 25 telescopes an open side of the smoke box, the cover plate being marginally flanged at 26 to carry out such fitting, the flange being secured detachably at 27 to the smoke box. This cover plate has an opening 28 to accommodate the inner washers and nuts 23 and 24. The casting or plate 22 is secured by bolts 29 to the cover plate, there being a relatively heavy gasket 30 between the casting plate and cover plate to prevent seeping of the water into the smoke box. A reinforcing plate 31 is located adjacent the inner surface of the cover plate and also receives the bolts 29, the reinforcing plate acting to brace the cover plate and render the same more durable as the cover plate is removable at times. In other words, the removal of the cover plate permits access to the interior of the smoke box for cleaning the same, and due to the removability, the cover plate is subjected to considerable wear and rough usage.

The other ends of the pipes or tubes 21 are threaded through a casting 32 which, in turn, is secured by bolts 33 to a cover plate 34. The cover plate 34 is also marginally flanged, as at 35, to telescopically and detachably fit the open end of the fire-box. The flange 35 of the cover plate 34 is secured to the wall of the fire-box.

A relatively heavy gasket 37 is positioned between the casting 32 and the cover plate 34, which has an opening through which the pipes or tubes 21 partially pass, and disposed adjacent the inner face of the cover plate 34 and also secured by the bolts 33 is a reinforcing plate 38 which is similar to the plate 31, the same being designed to brace the cover plate and to insure a rigid con-

struction as well as rendering the plate more durable.

In use, the heater is placed within a suitable tank which is adapted to contain water to be heated, then fuel is allowed to pass through the chute or passage, when the deflector 12 is disposed as in dot and dash lines, for the purpose of conveying the fuel to the fire-box. After the fire is lighted and thoroughly started, the deflector may be disposed as in full lines and the damper or cover 15 adjusted to provide the proper draft. By this improved construction of heater, the water in the tank can be easily and very quickly heated for use by live stock or the water may be used for other purposes.

When it is desired to clean the fire-box, the grate is removed. The grate being loosely mounted in the fire-box, it may be withdrawn through the chute portion 7 after shifting the damper to its full open position. Then the ashes and unburned fuel may be removed by a hoe or other implement, withdrawing it up the chute.

As a means for securing the device in the tank 1, anchoring members are employed. These consist of bars 40 transversely spanning the fire-box and the smoke box and engaged by the threaded extremities of eye-bolts 41 which pass through the eyes in the bars and receive nuts 42 bearing upon the top of the bars. The eyes 43 of the eye-bolts engage anchoring hooks 44 riveted or otherwise secured to the bottom of the tank.

The invention having been described, what is claimed is:

A heater for submersion in a water tank comprising spaced casings of which one is provided with a fuel feed chute and the other with a smoke flue, the facing ends of said casings being provided with cover plates having castings mounted thereon, and tubes threadingly engaged with one casting and extended through the other and provided with nuts engaging the opposite faces thereof.

In testimony whereof he affixes his signature.

ADOLF B. HROMAS.
